UNITED STATES PATENT OFFICE

ARNOLD MOETTELLI, OF OBERWINTERTHUR, SWITZERLAND, ASSIGNOR TO THE FIRM:
DRY QUENCHING EQUIPMENT CORPORATION, OF NEW YORK, N. Y.

APPARATUS FOR THE DRY-COOLING OF COKE

Application filed November 21, 1927, Serial No. 234,626, and in Switzerland November 22, 1926.

The invention relates to an installation intended for the dry-cooling of incandescent coke.

To this end at least one container receiving the coke to be cooled is run into a chamber arranged on the floor level of the installation, the walls of the chamber being lined with hollow bodies, through which a cooling medium flows and which are connected to a heat exchanger.

The hollow bodies may be designed as tubes and connected to a boiler drum arranged above them and acting as a heat storage member. In larger installations of this type, it is of advantage to subdivide the chamber intended to receive the incandescent coke, into two or more compartments which are separated from one another by heat exchanging tubes. Spaces may be left free between the tubes, the side walls of the chamber and the side walls of the coke containers, which spaces enable a circulation of the gaseous contents of the chamber.

An embodiment of the subject-matter of the invention is illustrated by way of example in the drawings, which accompany and form part of this specification. In these drawings:

Figure 1 is an elevation of the installation designed in accordance with my invention, partly in section.

Figure 2 is a section on line II—II of Figure 1, and

Figure 3 is a sectional view, similar to that of Figure 2, of a modified form of the installation.

Referring now to these drawings, *a* denotes the oven battery of a gasworks, from which the incandescent coke is supplied to the cooling plant working on the dry process, by means of containers *b* running on rails *c*. This cooling installation consists of a chamber *d* adapted to be closed on all sides. The coke containers *b* may be run into this chamber without being raised or lowered by any lifting device. The side walls of the chamber *d* are lined with water tubes *e*. The tubes *e*, together with a boiler drum *f* joined to them above and a collector *g* joined to them

below, form a sort of vertical water tube boiler.

The installation operates in the following manner:

The incandescent coke delivered from the coke ovens is run by means of the containers *b* into the chamber *d*, after the door *h* of the latter has been opened. The door *h* is then closed and the coke remains in chamber *d* until it has sufficiently cooled down. The sensible heat of the coke is thereby transmitted to the contents of the boiler, principally by radiation, which contents, according to the conditions prevailing, are either brought to a higher temperature or evaporated. After the coke has cooled down to about the boiler temperature, the opposite door *i* is opened and the coke is withdrawn from the cooling chamber *d* in the same containers *b* in which it has been introduced, this being effected by running the container *b* on the prolongation *k* of the track *c*.

The tubes *e* are arranged at a certain distance away from the side walls of the chamber *d*, to enable a circulation of the gaseous contents of the latter in the direction of the arrows, Figure 2, whereby the heat transmission is favored. To this latter end, suitable directing walls or other baffle means may further be provided between the tubes *e*.

Figure 3 illustrates a somewhat modified cooling installation according to my invention, comprising two coke containers arranged beside one another; in this installation water tubes are provided also between the two coke containers. By charging the two compartments of a chamber of this type alternately, the heat transfer to the boiler is rendered more uniform. Instead of two compartments, as illustrated, a plurality of them may of course be provided. In transmitting heat to the boiler the water tubes located in the vicinity of the doors act as down tubes, whilst the other tubes act as risers, a satisfactory water circulation thus being ensured.

The coke containers *b* are equipped with rollers *m* enabling them to travel on their trucks *l*, so that the containers may be pushed into the cooling chamber without the trucks *l*.

The latter are thus protected as far as possible from the noxious action of the heat.

What I claim and desire to secure by Letters Patent, is:—

- 5 1. An installation for the dry cooling of incandescent coke and the like comprising a chamber, a boiler comprising a lower header, an upper drum and rows of upright tubes communicably connecting said header and 10 said drum, said tubes being arranged with one row lining one side wall of the chamber and another row lining the opposite side wall of the chamber, a hot coke container, and means for conveying said container into said 15 chamber.
2. An installation for the dry cooling of incandescent coke and the like comprising a chamber, a boiler comprising a lower header, an upper drum, rows of upright boiler tubes 20 communicably connecting said header and said drum, said tubes being arranged with one row lining one side wall of the chamber, another row lining the opposite side wall and another row intermediate of said rows 25 so as to divide the said chamber into two compartments, the intermediate row constituting a common wall for both compartments, coke containers, and means for conveying said containers into said compartments.
- 30 3. An installation for the dry cooling of incandescent coke and the like comprising a chamber, a boiler comprising a lower header, an upper drum, rows of upright boiler tubes communicably connecting said header and 35 said drum, said rows being arranged so as to provide water walls for said chamber and so as to divide said chamber into a plurality of compartments, and a plurality of hot coke containers adapted to be conveyed into said 40 compartments.

In testimony whereof I have affixed my signature.

ARNOLD MOETTELLI.
